UNITED STATES PATENT OFFICE.

CHARLES HENRY LADEW, SR., OF NEW YORK, N. Y., ASSIGNOR OF ONE-HALF TO JOSEPH W. BIRNBAUM, OF NEW YORK, N. Y.

PEDAL-ACTION FOR PLAYER-PIANOS.

1,128,882.

Specification of Letters Patent. Patented Feb. 16, 1915.

Application filed May 27, 1914. Serial No. 841,219.

To all whom it may concern:

Be it known that I, CHARLES H. LADEW, Sr., a citizen of the United States, and a resident of the city of New York, borough 5 of the Bronx, in the county of Bronx and State of New York, have invented a new and Improved Pedal-Action for Player-Pianos, of which the following is a full, clear, and exact description.

10 The object of the invention is to provide a new and improved pedal action for player pianos, arranged to control the hammer rail and the damper rail of the piano action in the usual manner when playing the piano 15 by hand, or to permit of actuating the bellows from the same pedals when using the instrument as a player piano.

In order to accomplish the desired result, use is made of a coupling adapted to couple 20 a pedal with the rail actuating mechanism of the piano action or with the actuating device for the bellows.

A practical embodiment of the invention is represented in the accompanying drawings 25 forming a part of this specification, in which similar characters of reference indicate corresponding parts in all the views.

Figure 1 is a plan view of the pedal action with the couplings in position to connect 30 the usual loud and soft pedals with the actuating mechanisms of the bellows; Fig. 2 is a cross section of the same on the line 2—2 of Fig. 1; Fig. 3 is a plan view of one of the 35 pedals and its coupling connected with the corresponding lifter lever; Fig. 4 is a sectional front view of the pivotal connection of a pedal and the lever for actuating the bellows, the section being on the line 4—4 of Fig. 2; and Fig. 5 is a sectional front view 40 of the coupling in position for connecting a pedal with the lifter levers, the section being on the line 5—5 of Fig. 3. Figs. 6, 7 and 8 are sectional views showing the interior of a player piano and the connections 45 between the rail, the rail lifters, the bellows, bellows levers, and the pedals.

The player piano is provided with the usual three pedals, A, B and C, of which the side pedals A and B are adapted to actuate 50 the lifter levers D, D' for controlling the hammer rail and the damper rail of the piano action in the usual manner when playing the piano by hand, or the said pedals A

and B are adapted to be connected with the actuating levers E and E' for the bellows whenever the piano is used as a player piano. It is understood that when the 55 pedals A and B are connected with the levers D and D' they are disconnected from the actuating levers E and E' for the bellows, and when the pedals A and B are connected with the said actuating levers E and E' they are disconnected from the levers D and D'. In order to accomplish 60 the desired result use is made of a coupling F on each pedal A and B. The coupling is in the form of a plate F' arranged on the under side of the corresponding pedal A or B. The plate F' is provided with slots F² through which extends screws G screwing 70 in the pedal A or B to permit of sliding the plate F' forward or backward on the corresponding pedal A or B. The forward end of the plate F' is provided with a button F³ under the control of the user of the player 75 piano to permit the user to conveniently shift the coupling into either of its two active positions. The rear end of the plate F' is provided with an upwardly extending loop F⁴ adapted to engage the forward end 80 of a lever E² forming part of the corresponding pedal actuating mechanism E or E'. The lever E² is fulcrumed on a pivot H which also forms the fulcrum for the corresponding pedal A or B, and the lever E² 85 is pressed on by a spring I and its rear end is provided with a friction roller E³ engaging a slot E⁴ in a bell crank lever E⁵ connected by a link E⁶ with the movable member of the corresponding bellows. It will 90 be noticed that when the loop F⁴ engages the lever E², as shown in Fig. 2, then the said lever is coupled to the corresponding pedal A or B and consequently when the 95 pedal is alternately pressed and released, a swinging motion is given to the lever E² whereby the bell crank lever E⁵ is actuated and with it the corresponding bellows. Now on pressing the pedals A and B alternately up and down the bellows are actuated in the 100 usual manner.

Each plate F' is provided with a sidewise extending arm F⁵ adapted to engage a slotted keeper D² or D³ attached to the corresponding lifter lever D or D'. The arm F⁵ is so 105 arranged relatively to the loop F⁴ that when

the loop F^4 engages the lever E^2 the arm F^5 is out of engagement with the slotted keeper D^2 , and when the coupling is shifted forwardly then the loop F^4 disengages the lever E^2 while the arm F^5 moves into engagement with the keeper D^2 to connect the corresponding pedal with the corresponding lever D or D' , and at the same time the corresponding pedal is disconnected from the lever E^2 of the corresponding bellows actuating mechanism E or E' . When the pedals A and B are now pressed they actuate in the usual manner the hammer rail or the damper rail, as the case may be, of the piano action.

From the foregoing it will be seen that it is not necessary to use separate pedals for actuating the bellows as the regular soft and loud pedals of the piano action are used for actuating the bellows and it is only necessary for the user to shift the couplings F from one position to the other to allow the use of the pedals A and B for actuating the bellows or the hammer and damper rails. It will further be noticed that the rearwardly folding bellows actuating mechanism heretofore used is entirely dispensed with and the appearance of the pedals is the same as in ordinary pianos now in use.

Having thus described my invention, I claim as new and desire to secure by Letters Patent:

1. A pedal action for player pianos comprising in combination a pedal, a rail lifting lever, a bellows actuating lever, and means for manually connecting or disconnecting said pedal with said rail lifting lever or the bellows actuating lever.

2. A pedal action for player pianos comprising a pedal, a rail lifting lever and a bellows actuating lever, and a manually controlled coupling adapted to connect said pedal with said rail lifting lever or with said bellows actuating lever.

3. A pedal action for player pianos, comprising a pedal, a rail lifting lever, a bellows actuating lever, a manually controlled coupling carried by said pedal and adapted to connect said pedal with the rail lifting lever or with the bellows actuating lever to allow of actuating the rail lifting lever on manipulating the pedal or to allow of actuating the bellows actuating lever on manipulating the pedal.

4. A pedal action for player pianos, comprising a pedal, a manually controlled coupling adapted to connect said pedal with a rail lifting lever or with a bellows actuating lever to allow of actuating the rail lifting lever on manipulating the pedal or to allow of actuating the bellows actuating lever on manipulating the pedal.

5. In a player piano, the combination of a rail lifting lever, a bellows actuating lever, a pedal, and a coupling capable of being moved

into two positions, the coupling in one position connecting the said pedal with the said rail lifting lever and the said coupling in the other position connecting the said pedal with the bellows lifting lever.

6. In a player piano, the combination of rail connections, bellows connections, pedals, and couplings slideable on the said pedals and each adapted to be moved into two positions, the couplings in one position connecting the said pedals with the said rail connections and the said couplings in the other position connecting the said pedals with the said bellows connections.

7. In a player piano the combination with a piano pedal consisting of two members overlapping at their ends, one member being pivotally supported and adapted to be operably connected with a bellows actuating lever, of a coupling member comprising a box-like loop embracing the aforesaid overlapped ends, and slideable thereon, an extension projecting forwardly from said loop and adapted to be used as a handle to slide the coupling member rearwardly to couple the pedal with the bellows actuating lever and forwardly to uncouple said parts.

8. In a player piano, the combination of a piano pedal, a coupling mounted to slide on the said pedal, a bellows actuating lever adapted to be engaged by the said coupling to actuate the lever and bellows on manipulating the pedal, and a rail lifter lever adapted to be engaged by the said coupling to actuate the rail on manipulating the said pedal.

9. In a player piano, the combination with a piano pedal, of a coupling member comprising a box-like loop embracing the pedal and slideable thereon, a member extending forwardly from said loop beneath the pedal and serving as a handle a rail lifting lever and a horizontal arm extending transversely from said forwardly extending member, and adapted to operably engage the said rail lifting lever.

10. In a player piano, the combination of a piano pedal, a coupling mounted to slide on the said pedal, a bellows actuating lever adapted to be engaged by the said coupling to actuate the said lever on manipulating the said pedal, a rail lifter lever, and a coupling member on the said rail lifter lever and adapted to be engaged by the said coupling on moving the latter out of engagement with the said bellows actuating lever.

11. In a player piano, the combination of a pedal having a pivot at its rear end, a coupling mounted to slide on the said pedal and having a loop, a sidewise extending arm, and a handle extending forward under the pedal, a bellows actuating lever fulcrumed on the said pivot independent of the said pedal, the said lever being adapted to be engaged by the said loop to lock the lever to

the said pedal, and a rail lifter lever having a keeper adapted to be engaged by the said coupling arm.

12. In a player piano, the combination of
5 a pedal having a pivot at its rear end, a
coupling mounted to slide on the said pedal
and having a loop, a sidewise extending arm
and a handle extending forward under the
pedal, a bellows actuating lever fulcrumed
10 on the said pivot independent of the said
pedal, the said lever being adapted to be en-
gaged by the said loop to lock the lever to
the said pedal, and a rail lifter lever having
a keeper adapted to be engaged by the said
15 coupling arm, the said coupling on being
moved rearward coupling the pedal to the
said bellows actuating lever and uncoupling
the pedal and the rail lifter lever, and the
said coupling on being moved forward cou-
20 pling the pedal with the said lifter lever and
uncoupling the bellows actuating lever from
the pedal.
13. In a player piano, the combination of
25 a pedal having a pivot at its rear end, a cou-
pling mounted to slide on said pedal and
having a loop, a sidewise extending arm and

a handle extending forward under the pedal,
a lever fulcrumed on said pivot independent
of the pedal and forming part of the bel-
lows actuating mechanism said lever adapt-
30 ed to be engaged by said loop to lock the
lever to the pedal, and having a slot at its
rear end, an antifriction roller journaled in
said slot, a bell crank lever having a slotted
arm engaged by said antifriction roller, a 35
spring for controlling the slotted lever, and
a rail lifter lever having a keeper adapted
to be engaged by the aforesaid coupling arm,
the said coupling on being moved rearward
40 coupling the pedal to the said bellows actu-
ating lever, and uncoupling the pedal and
the rail lifter lever and the said coupling on
being moved forward coupling the pedal
45 with said lifter lever and uncoupling the
bellows actuating lever from the pedal.

In testimony whereof I have signed my
name to this specification in the presence of
two subscribing witnesses.
